SLIDING DOOR TRACK AND HANGER.

No. 380,299.

Patented Mar. 27, 1888.

UNITED STATES PATENT OFFICE.

HENRY SOULEN, OF MILWAUKEE, WISCONSIN, ASSIGNOR TO THE WILLIAM LUITINK & SONS MANUFACTURING COMPANY, OF SAME PLACE.

SLIDING-DOOR TRACK AND HANGER.

SPECIFICATION forming part of Letters Patent No. 380,299, dated March 27, 1888.

Application filed July 11, 1887. Serial No. 243,997. (No model.)

To all whom it may concern:

Be it known that I, HENRY SOULEN, of the city and county of Milwaukee and State of Wisconsin, have invented certain new and useful Improvements in Sliding-Door Tracks and Hangers; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The objects of my invention are, first, to maintain the adjustment of the track whereby the doors are caused to make a perfect joint with each other when closed and to cause their edges to stand flush or parallel with the side jambs or door-frame when they are withdrawn into the pockets in the wall or partition; second, to facilitate setting the track in finished walls or partitions without breaking the plaster or mutilating the finish; and, third, to prevent the binding and facilitate the working of the doors.

It consists, essentially, of a track-box provided with rails for the hanger-wheels to run upon, supported at the sides of the door-opening and at the center of the opening, (when used with double doors,) and sustained at the end which projects into the pocket by a truss-rod provided with an adjusting-nut accessible through the opening between the head-jambs, of interchangeable pocket-pieces, and of other features hereinafter fully described.

In the accompanying drawings like letters designate the same parts in the several figures.

Figure 1 is a vertical longitudinal section of one section of my improved sliding - door track. Fig. 2 is a cross-section of the same on an enlarged scale, taken on the line *x x*, Fig. 1. Fig. 3 is a similar section of one side of the track on the line *y y*, Fig. 1. Fig. 4 is a like section on the line *z z*, Fig. 1. Fig. 5 is medial longitudinal section, on an enlarged scale, taken on the line *w w*, Fig. 4, of the adjacent ends of the track-sections, the coupling and central adjusting device, and a portion of a door and hanger. Fig. 6 is a detail in side elevation of one of the pocket-pieces. Fig. 7 is a section on the line *v v*, Fig. 4,

showing in plan the central track connecting and adjusting device. Fig. 8 is a horizontal section on the line *r r*, Fig. 4, showing a plan view of the central track-support and door-stop. Figs. 9 and 10 are details of a modified form of the track-supports employed at the sides of the door-opening, and Fig. 11 is a plan view of one of the door-plates for the attachment of the hanger.

Since for double doors the track-box is made in two sections which are joined at the center of the door-opening and are exactly alike, but one section is shown complete in the drawings. One of these sections may be adapted by slight modifications for use with a single door.

Referring to the drawings, A A represent the track-boxes, each composed of a top and two sides, to the lower edges of which are secured on the inside of the box the rails *a a*. Each of these boxes (when two are employed for double doors) is supported at or near the sides of the door-opening just inside of the jambs by brackets E E, screwed to the studing N N, and by adjusting-bolts *e e*, which are formed on the heads, with annular flanges resting upon said brackets E E, and engage and work with nuts *e' e'*, attached to the lower edges of the boxes A A on each side thereof. These brackets E and bolts *e* serve as fulcrums, upon which the boxes may be adjusted, so as to elevate or depress either end, as desired.

C C are yokes attached one to each box A near the center adjacent to the supporting-brackets E. These yokes C C are formed on the upper side directly over the center of the boxes with upwardly - extending perforated ears or bridges *c c*, and extending over and embracing the sides of said boxes to prevent the spreading of the rails *a a*.

To the ends of the boxes A A, at the center of the upper side thereof, are secured perforated ears D D. Each box A is provided with a truss-rod, B, inserted at the ends through the perforated ears D D and extending over or through the bridge *c*, near the middle of the box. At the end adjacent to the center of the door-opening each of the truss-rods is threaded and provided with a circular nut, *b*, the rim of which is notched, so as to be turned by a screw-driver or other suitable instrument inserted through the opening between the head

jambs P P and track-rails. The truss-rod is held in the ears D at the opposite end of the box by a head or nut. Adjacent to each yoke C the boxes A A are transversely cut through 5 the top and side, as at a', Fig. 1, down to the rails a a, so as to render them flexible at those points.

At the center of the double door opening is secured to the headers N' N', by means of 10 screws r' r', the cross-piece K, as shown in Figs. 4 and 8, which is perforated at the center and recessed on the under side to receive the head-flange of the adjusting-bolt I. The 15 perforated plate K', bolted or riveted to the under side of said cross-piece K, retains the adjusting-bolt I therein and furnishes a fixed bearing therefor, the slotted head of said bolt being exposed below through the opening in said plate.

20 Directly above the cross-piece K a yoke, J, formed with a central nut to receive and work with the adjusting-bolt I, is attached to and connects the adjacent ends of the boxes A A. The rails a a are cut off, so as to allow the 25 insertion of the hanger-wheels F' F' between them, and the opening thus formed is closed and the track made continuous by the insertion of the interchangeable pocket-pieces L L, which are T-shaped in cross-section and held 30 in corresponding grooves cut in the ends of the rails a a, Figs. 4 and 6. The cross-piece K is grooved or recessed on the edges, and between it and the plate K' are inserted rubber cushions k' k', against which the hanger-yokes 35 strike, thereby stopping the doors at the center of the opening.

M represents a portion of one of the doors, and F F the hanger-yokes or frames formed with cylindrical or rounded tenons which are 40 inserted in similarly-shaped grooves in the plates G G attached to the top of the door.

f f are the rider-bars secured in the upper ends of the yokes F F and resting upon the axles of the hanger-wheels F' F'. The rounded 45 tenons on the bases of yokes F and the grooves in the door-plates G are made tapering or conical and the yokes secured in said plates by screws g g, tapped into the ends of said plates and bearing at their heads or through 50 interposed washers against the larger ends of said tenons. The yokes, which work with stops k' k', being inserted into the grooved plates G G, from the inner edges of the doors, are thus 55 prevented from being loosened by the closing of the doors against said stops.

P P represent the door-jambs, p p the stops, and Q Q the casings, of the usual construction and arrangement.

60 Referring to Figs. 9 and 10, illustrating a modification of the device for supporting the track at the sides of the door-opening, O is a slide pivoted to the lower edge of the box A and resting upon the wedge S, which is grooved to receive and guide a tongue formed on the 65 under side of said slide, and in turn rests upon a shoulder cut into the adjacent stud N.

The setting, adjustment, and operation of

my improved track and hanger may be described as follows:

The brackets E E are attached to the studding adjacent to the sides of the door-opening, 70 at or near the top thereof, the boxes inserted in the wall between the studding, and the heads of the bolts e e placed in the openings in said brackets. The hanger-wheels are then introduced into the track-box through the pocket-openings in the rails a a, the pocket-pieces L L dropped into said openings in engagement with the grooves in the adjacent ends of said rails, and the yoke J attached to the sides of 75 the box sections. The adjusting-screw I is then turned into the central nut in said yoke J, and the cross-piece K, in which the head of said bolt bears, is secured at each end to the headers N' N' on each side of the pocket-opening in the wall. The doors are carefully 80 and accurately joined on their upper edges and the grooved plates G G attached thereto. The tenons on the hanger-yokes F F are then inserted endwise into the grooves in said plates 85 G G, and the hanger-frames adjust themselves 90 to a position parallel with the faces of the doors, when the weight of the doors is suspended by said yokes upon the axles of the hanger-wheels F' F'. When properly adjusted, 95 by turning the cylindrical tenons in the grooves of the door-plate each hanger-frame is secured in its proper position by tightening the screw g, which wedges the tapering tenons snugly 100 into the grooves in said door-plates, and thereby prevents the hanger-frame from turning laterally.

To place my improved track in finished walls or partitions requires simply the removal of the door-jamb and occasionally the cutting 105 away of the studding in the pockets to receive the track-boxes. The ease with which my track may be placed in finished walls without injury thereto constitutes one of its chief advantages. Having been set in position, as described, the track is leveled by turning the central adjusting-bolt, I, which raises or lowers the inner ends of the track boxes or sections at the center of the door-opening, as required, and the opposite ends of the box-sections in the pockets are then brought into line 110 with that portion of the track or box between the sides of the door-opening, or the cuts a' a' at the middle of each box-section, by turning the adjusting-nuts b b, which operate through 115 the truss-rods B B to elevate or depress the opposite ends of the track, as required. If necessary, the entire track may be raised or lowered by turning the adjusting-bolts e e, upon which the box-sections are supported 120 adjacent to the side jambs, or the same result may be accomplished when the device illustrated in Figs. 9 and 10 is employed, by moving the wedges S longitudinally, so as to raise or 125 lower the blocks O. Either side of the track-box, with the rail a attached thereto, may be raised or lowered to adjust it to the level of the other side or rail by means of the adjusting-bolt e on the corresponding side.

As heretofore constructed the pocket-pieces have required independent fastenings to hold them in place; but my improved pocket-pieces, formed with central vertical webs or flanges, which, dropped from above into corresponding grooves in the ends of the rails *a a*, require no separate fastenings and possess the advantage of being interchangeable and being more easily and quickly set. Whenever, by the warping or settling of the walls, the track becomes distorted and the doors work imperfectly they can be readily readjusted, by means of the adjusting-bolt *I* and the adjusting-nuts *b b*, without disturbing the door frame or casings. The ends of the track box and rails in the pockets being adjustable independently of that portion of the box-sections or track directly above the door-opening permit of the adjustment of the track, so as to cause the doors when closed to meet and form a perfect joint with each other, and their inner edges to stand flush or parallel with the side jambs when they are opened and withdrawn into the pockets. By constructing the central cross-support, *K*, and providing it, as described, with cushions *k' k'*, the stops ordinarily attached to the outer edges of each door are dispensed with.

It will be seen by reference to Figs. 1 and 5 that the yokes *F F* next to the stop *K* are formed with shoulders or offsets which pass closely under said stop, and thereby prevent the inner edges of the doors from jumping up and the bottoms from clearing the pockets and floor-guides when the doors are run violently against said stop.

I claim--

1. The combination, with a sliding door and its hangers, of a track and truss-rod attached to the ends of said track and provided at one end with an adjusting-nut, substantially as and for the purposes set forth.

2. The combination, with a sliding door and its hangers, of a vertically-adjustable track supported at the middle and at one end, a truss rod attached to the ends of said track and passing over a bridge at an intermediate point thereof, and an adjusting-nut applied to one end of said truss-rod, substantially as and for the purposes set forth.

3. The combination, with a sliding door and its hangers, of a track-box provided with rails for the hanger-wheels, and transversely cut through the top and sides at an intermediate point, a truss-rod secured at the ends to the ends of said box and passing over a bridge attached thereto adjacent to its transverse cut, and an adjusting-nut applied to one end of said truss-rod, substantially as and for the purposes set forth.

4. The combination, with a pair of sliding doors and their hangers, of a pair of track boxes or sections provided with rails for the hanger-wheels and each supported at the side of the door-opening, a yoke connecting said boxes above the center of the door-opening and provided with a nut, an adjusting-screw

having a fixed bearing and working with said nut, and truss-rods attached at their ends to the ends of said track-boxes, and provided with adjusting-nuts for raising and lowering the outer ends of said track-boxes, substantially as and for the purposes set forth.

5. The combination, with a sliding door and its hangers, of a track-rail having a break or opening for the insertion of the hanger-wheels and formed at the ends adjacent to said break or opening with T-shaped grooves or recesses, and a removable pocket-piece formed at the ends with similarly-shaped tongues or flanges adapted to enter said grooves from above and retain said pocket-piece in place to bridge said break or opening and form an unbroken way for said hanger-wheels, substantially as and for the purposes set forth.

6. The combination, with sliding doors and their hangers, of a track-box provided on the inside with rails for the hanger-wheels and composed of two sections, a yoke or plate connecting said sections above the center of the door-opening and formed with a nut, a fixed cross-support secured underneath said yoke, and an adjusting-bolt journaled in said cross-support and working with the nut in said yoke, substantially as and for the purposes set forth.

7. The combination, with a sliding door and its track, of hanger-wheels adapted to run on said track, a hanger-yoke formed with a tenon rounded in cross-section, and a door-plate attached to the upper edge of the door and formed with a corresponding groove for the reception of said tenon, substantially as and for the purposes set forth.

8. The combination, with a pair of sliding doors and their hangers, of a track-box composed of two sections connected above the center of the door-opening, and each supported at the sides of the door-opening upon vertical adjusting-bolts, and each provided with a truss-rod attached thereto at the ends and furnished with an adjusting-nut, and a vertical adjusting-bolt working above the center of the door-opening with said box and the fixed support, substantially as and for the purposes set forth.

9. The combination, with sliding doors, of a track above the door-opening, a stop located at or near the center of the upper side of said opening and provided on the opposite sides with elastic cushions, and hangers attached to the upper edges of the doors and formed with shoulders or offsets, which are arranged to pass closely under said stop before the movement of the doors is arrested by said stop, substantially as and for the purposes set forth.

In testimony that I claim the foregoing as my own I affix my signature in presence of two witnesses.

HENRY SOULEN.
